HARRY ROBERT NORTHOVER, OF WINNIPEG, MANITOBA, CANADA.

GAS-CYLINDER FOR MACHINE-GUNS.

1,234,071.

Specification of Letters Patent. Patented July 17, 1917.

Application filed November 23, 1915. Serial No. 63,104.

To all whom it may concern:

Be it known that I, HARRY ROBERT NORTHOVER, subject of the King of Great Britain, residing at 217 Graham avenue, 5 Winnipeg, Manitoba, in the Dominion of Canada, gunsmith, have invented certain new and useful Improvements in Gas-Cylinders for Machine-Guns, of which the following is a specification.

10 In gas-operated automatic or machine guns of the "Colt" type, the muzzle end of the detachable and interchangeable barrel is carried in, and connected to the front end of the gun-body by, an arm extending 15 forwardly from the barrel bracket, which arm is disposed below the barrel, and is provided, at its front end, with a sleeve or band wherethrough the said barrel is passed. The bottom of this band and the 20 part of the arm that comes underneath the same are formed with a gas-cylinder, which when the gun is assembled, registers or communicates with a barrel gas-vent wherethrough the powder-gas pressure acts upon 25 a piston that is contained in the said gas cylinder and is connected with a vertically swinging gas-lever of the breech mechanism.

In the "Colt" automatic gun, the band 30 of the gas-cylinder is made in the form of a solid or rigid sleeve, and the effective automatic action of the gun by the powder-gas pressure largely depends upon the existence of a good gas-tight joint between the barrel 35 vent and the gas-cylinder. To obtain such a good joint as will enable the gun to start working automatically after the first shot, the detachable barrel must be made a perfect fit within the gas-cylinder when the 40 gun is cold, but if such a fit is provided for under these conditions, it becomes a difficult matter to remove the barrel if the gun requires to be dismounted when hot from continuous firing. On the other hand, unless a 45 good initial fit exists between the barrel and gas-cylinder, it may be necessary before the gun will start working automatically, to fire a succession of shots and to operate the breech mechanism by manually working 50 the gas lever after each shot, in order that the barrel may expand under heat sufficiently to establish a perfectly tight joint between the barrel-vent and the gas-cylinder.

55 According to the present invention, and with the object of obviating the above-men-

tioned disadvantages, I propose to embody in the gas-cylinder, a band which is expandable and contractible and is adapted to be adjusted to or upon the dismountable 60 barrel by mechanical means, whereby a gas-tight joint can be obtained under all conditions, while the removal of the barrel, even when the gun is hot, is considerably facilitated. That is to say, instead of providing 65 the gas-cylinder with a barrel-band in the form of a solid rigid sleeve, I construct the same with an adjustable spring-clip or barrel-clamp which is capable of being tightened or slackened by a hand screw or 70 the like, and which can be closed or contracted around the barrel, on the latter being mounted on the gun, so as to establish a sufficiently gas-tight metal-to-metal joint in the region of the barrel vent to insure 75 that the gun will operate automatically after the firing of the first shot, while on slackening back the screw, the said clamp expands or opens out sufficiently to admit of the barrel being quickly detached and 80 dismounted.

Figure 1 of the accompanying drawing represents a top plan of a gas-cylinder for a "Colt" gun embodying an adjustable barrel-band in accordance with my invention.

Fig. 2 is a rear end elevation of the said gas-cylinder.

Fig. 3 is a bottom plan of the same, and

Fig. 4 is a side elevation, showing, in 90 dotted lines, the open-ended passage, or gas-cylinder proper, which is formed in the front end of the body of the device and communicates, in the assembled gun, with the gas-vent in the barrel.

Figs. 5 and 6 are, respectively, a vertical section and a plan view of a modification or development of the invention.

The same letters of reference indicate corresponding parts in the specification and 100 drawings.

In the construction shown, *a* is the body of the device and *b* is the band or sleeve wherethrough the barrel of the gun is passed; the circular boss *a*¹ at the forward 105 part of the said body *a* being formed with the open-ended passage, or gas-cylinder proper, *c* for containing the gas-operated piston which is connected with the oscillating lever of the breech mechanism. The 110 upper end *c*¹ of this cylinder opens into the bottom of the barrel-band *b* and communi-

cates directly with the barrel vent where-through the powder-gas pressure acts upon the piston when the gun is being fired.

In accordance with this particular form 5 of the invention the barrel-band is formed, along its right-hand side, with a split or division b^1 , and is also provided externally, on the opposite sides of the said split, with a pair of laterally-projecting ears or lugs b^2 , 10 b^3 , pierced with eyes or holes b^4 , b^5 (one plain and the other screwed) to take an adjusting screw d which is furnished with a lever or handle d^1 ; the arrangement being such that by rotating the screw in one direction, the split band is contracted or closed 15 around the barrel passing therethrough, whereas by turning the screw in the opposite direction, the said band is permitted to open out or expand by the natural spring of 20 the metal.

Thus, when the screw is slackened, the dismountable barrel of the gun may be readily passed through the band b so as to bring its gas-vent into register with the 25 gas-passage c , after which the contraction or adjustment of the band by means of the levered screw produces a perfectly gas-tight joint between the said band and barrel in the region of the gas-vent cylinder. On the 30 other hand, if it should be required to dismount or remove the barrel when hot from repeated firing, it is merely necessary to slacken the screw to allow the band to expand or open out sufficiently to permit of 35 the barrel being readily withdrawn.

A gas-cylinder such as above described can be readily fitted to existing "Colt" guns in the place of the ordinary solid-band form 40 of cylinder. Or existing cylinders may be adapted or altered so as to make them adjustable in accordance with my invention by splitting the barrel band and riveting or brazing lugs to take an adjusting screw or bolt to the exterior of the said band, on opposite sides of the split. Figs. 5 and 6 show 45 such an adapted cylinder; b being the barrel band, b^1 the longitudinal side split or division and b^2 , b^3 the attached adjusting-screw lugs which in this particular arrangement, are riveted to the outside of the band, on the opposite sides of the split.

It is obvious that, instead of the split or division being made at the side of the band as in the illustrated arrangements, the same 55 may be located at the top or any other convenient part; also that any form of screw or bolt may be adopted instead of that shown for mechanically adjusting the said band.

Having described my invention, what I 60 claim and desire to secure by Letters Patent is:

1. A gas-cylinder for Colt machine guns, embodying an expandable band or sleeve adapted to encircle the dismountable barrel 65 of the gun and provided with an open-

ended passage for the reception of the gas-lever piston which opens through the bottom of the band and is adapted to directly register with the gas-vent of the barrel; and means for contracting said band, so as to establish a gas-tight, metal-to-metal joint between the gas-vent and the piston-receiving passage.

2. A gas-cylinder for Colt machine guns, embodying an expandable split spring band 75 or sleeve adapted to encircle the dismountable barrel of the gun and provided with an open-ended passage for the reception of the gas-lever piston which opens through the bottom of the band and is adapted to directly register with the gas-vent of the barrel; and means for drawing the ends of 80 the band together, so as to establish a gas-tight, metal-to-metal joint between the gas-vent and the piston-receiving passage. 85

3. A gas-cylinder for Colt machine guns, comprising a split band or sleeve adapted to encircle the dismountable barrel of the gun; and means for drawing together the ends of the band, so as to contract said band 90 and thereby establish a gas-tight, metal-to-metal joint between the gas-vent of the barrel and the passage which receives the gas-lever piston.

4. A gas-cylinder for Colt machine guns, 95 comprising a split band or sleeve adapted to encircle the dismountable barrel of the gun and having laterally-projecting lugs at opposite sides of the split; and means for drawing said lugs together, so as to contract the band and thereby establish a gas-tight, metal-to-metal joint between the gas-vent of the barrel and the passage which receives the gas-lever piston. 100

5. A gas-cylinder for Colt machine guns, 10 comprising a split band or sleeve adapted to encircle the dismountable barrel of the gun and provided with laterally-projecting, apertured lugs at opposite sides of the split; and an adjusting member engaged in the apertures in said lugs, to draw the latter together, so as to contract said band and thereby establish a gas-tight, metal-to-metal joint between the gas-vent of the barrel and the passage which receives the gas-lever 11 piston. 11

6. A gas-cylinder for Colt machine guns, comprising a band or sleeve adapted to encircle the dismountable barrel of the gun, and a rearwardly-extending body portion 12 connected at its forward end to the bottom of said band and having its rear end adapted for connection to the barrel bracket, said body having its forward end provided with an open-ended passage for the reception of 12 the gas-lever piston which opens through the said band bottom and is adapted to directly register with the gas-vent of the barrel; said band being split transversely at one side thereof and provided at opposite 13

sides of the split with laterally-projecting lugs; and an adjusting member engaged with said lugs to force the same together, so as to contract the band and thereby establish a gas-tight, metal-to-metal joint between the gas-vent and the piston-receiving passage.

7. A gas-cylinder for Colt machine guns, comprising a band or sleeve adapted to encircle the dismountable barrel of the gun, and a rearwardly-extending body portion connected at its forward end to the bottom of said band and having its rear end adapted for connection to the barrel bracket, said body having its forward end provided with an open-ended passage for the reception of

the gas-lever piston which opens through the said band bottom and is adapted to directly register with the gas-vent of the barrel; said band being split transversely at one side thereof; and means for drawing the ends of said band together, so as to contract the band and thereby establish a gas-tight, metal-to-metal joint between the gas-vent and the piston-receiving passage.

In testimony whereof I have hereunto set my hand in presence of two subscribing witnesses.

HARRY ROBERT NORTHOVER.
